[57] **CLAIM**

The ornamental design for T-shirt configured car seat cover with magazine holder, as shown and described.

DESCRIPTION

FIG. 1 is a front elevational view of the first embodiment of the T-shirt configured car seat cover with magazine holder; FIG. 2 is a left side elevational view of both embodiments of the seat cover of this design. The right side is a mirror image thereof;

FIG. 3 is a rear elevational view of the first embodiment of this design;

FIG. 4 is a top perspective view of the first embodiment with the zipper closed;

FIG. 5 is a view similar to FIG. 4 but with the zipper open;

FIG. 6 is a right rear perspective view of the first embodiment, of this design disposed upon a car seat;

FIG. 7 is a right rear perspective view of the second embodiment of this design, done in non net fabric, disposed upon a car seat; and,

FIG. 8 is a view similar to FIG. 4, depicting the second embodiment done in non-net fabric.

The front of the second embodiment is the same as that of the first embodiment shown in FIG. 1.

“The broken line showing of environment in FIGS. 1, 6 and 7 is for illustrative purposes only and forms no part of the claimed design”.

“The crisscross shading of the pocket in FIGS. 3, 4, 5 and 6 is representative of net fabric”.
